UNITED STATES PATENT OFFICE.

MARTIN V. B. HOWE, OF ERVING, MASSACHUSETTS.

CHAIR-SEAT.

SPECIFICATION forming part of Letters Patent No. 275,383, dated April 10, 1883.

Application filed December 16, 1882. (No model.)

To all whom it may concern:

Be it known that I, MARTIN V. B. HOWE, a citizen of the United States, residing in Erving, in the county of Franklin and Commonwealth of Massachusetts, have invented 55 a new and Improved Chair-Seat, of which the following is a true and full specification.

It is a well-known fact not only to the manufacturers of chairs, but also to all who have 10 ever used cane-seat chairs, that besides the usual wear it often happens that the wooden frame of the chair splits out and lets the cane loose, and the chair is spoiled beyond repair. This is especially the case where, as in many 15 cases, bent frames are used. The ends of the wood, being upset in the bending, are very likely to split out, and so also are those frames which are tenoned together. The wood is often cross-grained, and the holes for the cane to 20 pass through rather large and near together. The strain upon the seat often splits out the frame, and in all these cases where the frame is split out the chair is entirely gone and cannot be repaired, as new holes cannot 25 be bored back for receiving the cane.

My invention is for a frame on which the cane is to be stretched, forming a seat independent of the chair-frame, and which is to be screwed or nailed upon the chair-frame, thus 30 completing the chair.

The accompanying drawings illustrate my invention and form part of this specification.

Figure 1 is a plan showing my chair-seat. Fig. 2 is a section on line $x-x$ of Fig. 1.

35 Similar reference-letters indicate like parts in both figures.

My seat-frame B is made of veneers or very thin boards, preferably what is called "three-ply," or with three thicknesses of veneer, having the grain of the wood of the middle piece 40 run at right angles to that of the piece glued on each side of it. Two-ply might do; but I prefer the three-ply, which makes the frame so strong that, though it is all together but an 45 eighth of an inch in thickness, the cane can never split it out on account of the grain of the wood in the three pieces running across each other. The frame B of this seat can be made of any shape, or, if made square, may be 50 easily cut to fit any chair-frame desired, and

it can be screwed on any chair-frame with screws of any style—gilt, plated, or blued—or nailed on with fancy nails, making a very handsomely-finished chair, and when the caning is worn out or broken by any accident the 55 seat can be easily and cheaply replaced by another, preserving the chair, which cannot be done with cane-seat chairs as at present constructed.

Another advantage of the frame made by 60 my invention is the saving of cane, which will be from one hundred to one hundred and fifty feet to each seat. The ordinary frame of a cane-seat chair being an inch or over in thickness, while mine is but one-eighth of 65 an inch thick, I save at least seven-eighths of an inch on every slip of cane put through each hole in making a seat—an important item in the cost of manufacture.

Another advantage in making the frame of 70 the seat of the crossed veneers and independent of the chair-frame is the ease and cheapness of transportation, which is an important consideration.

In chair-making it is common to have cane 75 seats bottomed away from the factory by men and women and children at their homes or in small shops, or in charitable or reformatory institutions. The frames are sent out, the cane put in, and the seat returned. The cost 80 of transportation is a large item of expense. As each of the ordinary chair-frames is an inch or more in thickness, and mine but one-eighth of an inch, the cost of transporting mine will be but one-eighth as much as on the present 85 frames.

The same invention may be used, if desired, in constructing the backs of chairs to be made in cane.

I am aware of the patent of Rowe, No. 90 244,769, which shows and describes a chair-bottom formed of a metal plate, upon which is secured a seat of paper perforated and eyeleted, and to such I make no claim, and over 95 which my chair-bottom has decided advantages, for the reason that a combination of wood veneers and interlaced cane, as an auxiliary seat, forms an article possessing obviously much superior qualities to recommend it to the trade.

What I claim in the manufacture of chairs
is—

As an improved article of manufacture, the
chair-bottom described, composed of wood
5 veneers, provided with a seat-opening which
is covered with a seat of interlaced cane strips,
said bottom being auxiliary in its application

to a chair-frame, substantially as and for the
purpose set forth.

MARTIN V. B. HOWE.
